United States Patent

Des. 235,680
Patented July 1, 1975

235,680

CLOCK RADIO

Tomio Fujiwara, Osaka, and Benito Mishiro, Sakai, Japan,
assignors to Matsushita Electric Industrial Co., Ltd.,
Kadoma, Japan

Filed Apr. 20, 1973, Ser. No. 353,171

Claims priority, application Japan Oct. 20, 1972

Term of patent 14 years

Int. Cl. D14—03

U.S. Cl. D56—4 B

FIG. 1

FIG. 2

FIG. 1 is a right side, top and front perspective view of a clock radio, showing our new design; and

FIG. 2 is a left side, top and rear perspective view.

Portions of the figures are shaded to indicate contrast in appearance, and portions are diagonally lined to indicate transparency.

A portion of the pattern of circles on the top of the clock radio has been omitted for convenience of illustration.

We claim:

The ornamental design for a clock radio, as shown and described.
